UNITED STATES PATENT OFFICE.

ADOLPH G. KAUFMAN, OF NEW YORK, N. Y.

LAMP-SHADE.

1,319,092.

Specification of Letters Patent.

Patented Oct. 21, 1919.

Application filed August 10, 1918. Serial No. 249,239.

To all whom it may concern:

Be it known that I, ADOLPH G. KAUFMAN, a citizen of the United States, residing at New York, in the county and State of New 5 York, have invented a new and useful Lamp-Shade, of which the following is a specification.

This invention relates to lamp shades; and the object thereof is to provide a collapsible shade which is easy to ship as it will occupy comparatively little space in shipping; and when in use the frame is rigidly held together so that it can be covered with silk, or any desired fabric, or other 15 material.

The invention is illustrated in the accompanying drawing, in which—

Figure 1, is a sectional view of a lamp shade constructed in accordance with my invention, the section being on the line 1—1 of Fig. 2, and the fabric, silk, or other material being shown partly in place;

Fig. 2, is a plan view of the frame;

Fig. 3, is a sectional view, similar to Fig. 25 1 without the covering, showing a modified form of construction;

Fig. 4, is a detail of construction on an enlarged scale; and,

Fig. 5, is a view of another detail of construction.

In the drawing like numerals of reference refer to the same parts in each of the views.

In practice I provide a lamp shade comprising a frame 6, preferably constructed 35 of wire, and a covering 7, composed of silk, fabric, or any desired material.

The purpose of the invention being to make a collapsible shade which can be shipped in a flat condition, I prefer to make 40 the frame of wire, comprising a wire ring 8, the ends of which may be frictionally held together with a sleeve 9, or the sleeve 9 may be secured in place with solder, or other material as this part will lie flat

45 in shipping; a plurality of risers 10, each of which is provided with an angled portion 11, adapted to pass through a housing, or keeper 12, secured to the ring 8, and each riser is provided with a head 13 of a size sufficient to prevent the angled portion being drawn through the housing 12, thereby 50 hinging the risers in the housing in a manner so that the same may be turned down into the same plane as the ring 8 in shipping; a ring 14, smaller in diameter than the ring 8 so that when the risers 10 are in

engagement therewith they will stand inclined, as shown in the drawing so that the silk covering 7 will stand in an inclined manner, as clearly shown, the keepers 15, on 60 the ring 14 serving to hold the risers 10 in engagement with the ring 14 in a detachable manner; and a central ring 16, held in a rigid manner with the stays 17 relative to the ring 14.

In operation the ring 16 is made of a size to engage a lamp chimney; and is held on a plane a little below the ring 14 so that when in engagement with a chimney the cover 7 will substantially conceal the ring 16, and 70 practically conceal the stays 17. The rings 16 and 14 are always in fixed relation to each other owing to the rigid connection by the stays 17; but the planes on which these two rings are held are so nearly on the 75 same plane that it is immaterial in shipping that this part should be collapsible.

When it is desired to ship the shade the risers 10 are withdrawn from the keepers 15 on the ring 14, and are then turned down 80 to the same plane as the ring 8 so that the upper part of the frame and the lower part with the risers can be packed and shipped in a substantially flat manner.

When it is desired to use the lamp shade 85 the risers 10 are brought into engagement with the keepers 15 on the ring 14; and when all are in engagement a substantially rigid frame will be formed which will hold a cover of silk, or other suitable material in 90 the proper and desired position to form a shade. Thus I provide a lamp shade that can be collapsed and shipped in the smallest possible space; and which can be made cheaply, and is efficient in use.

In Fig. 3 the only modification is the ring 18, slightly less in diameter than the ring 14; and held above the ring 14 with stays 19, which are turned inward, as shown so that the shade may be tied around the frame 100 by passing a cord, or any desired device around the shade between the rings 14 and 18, as will be understood. As the ring 18 is the only modification I have used the reference numerals 6, 8, 10, 11, 12, 13, 14, 105 16, and 17 without the prime mark.

The usefulness and value of the invention will be readily seen by anyone familiar with the art. A lamp shade is a bulky article for shipment in comparison with its weight; 110 and in shipment is easily crushed. Even where a silk shade is shipped having a wire

frame for holding the shade, the wire frame is frequently distorted. In the construction here shown, however, the frame can be shipped substantially flat; and when the shade reaches the customer, the frame can be quickly assembled to hold the silk shade in the proper position; and when assembled the frame can be easily mounted on a lamp owing to the positioning and holding of the 10 ring 16.

I claim:

1. A lamp shade comprising a wire frame, and a cover of flexible material, said frame comprising an upper and a lower ring hinged 15 together in a detachable manner, the upper ring being less in diameter than the lower

ring, an inner ring on substantially the same plane with the upper ring and rigidly connected therewith, said inner ring being adapted to engage a lamp chimney, and a 20 fourth ring mounted above the upper ring in a manner whereby a cord may be tied around the shade between the same, for the purpose set forth.

2. In a lamp shade, a hinged joint comprising a housing, and a wire having an angled portion passing through said housing, said angled portion having a head whereby it is prevented leaving the housing. 25

Dated this 8th day of August, 1918.

ADOLPH G. KAUFMAN.
